MANUALLY PROPELLED WATER-CRAFT

John W. Love, 18530 S. Broadway, Gardena, Calif.

Filed July 18, 1960, Ser. No. 61,385

Term of patent 14 years

(Cl. D71—1)

FIG. 1 is a side elevational view of a manually propelled water-craft showing my new design,

FIG. 2 is a top plan view thereof,

FIG. 3 is a bottom plan view thereof,

FIGS. 4 and 5 are, respectively, front and rear elevations thereof,

FIG. 6 is a reduced scale, longitudinal section taken on the line 6—6 of FIG. 2, and

FIG. 7 is a reduced scale, transverse sectional view taken on the line 7—7 of FIG. 1.

I claim:

The ornamental design for a manually propelled water-craft, substantially as shown.
